(57) **CLAIM**

The ornamental design for a mosquito killer lamp, as shown and described.

DESCRIPTION

FIG. 1 is a front, left and top perspective view of a mosquito killer lamp showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the mosquito killer lamp that form no part of the claimed design. The unshaded portions between broken and solid lines forms no part of the claimed design.

1 Claim, 8 Drawing Sheets
